INDEX CARD HOLDER

Ira Saltz, Greenlawn, N.Y., assignor to Oxford Pendaflex
Corporation, Garden City, N.Y.

Filed Sept. 23, 1971, Ser. No. 183,300

Term of patent 14 years

Int. Cl. D19—02

U.S. Cl. D74—2 A

FIG. 1

FIG. 2

FIG. 3

FIG. 1 is a front perspective view of an index card holder showing my design;

FIG. 2 is a left-side view thereof, the side opposite thereto being similar in appearance;

FIG. 3 is a top view; and

FIG. 4 is a front view thereof.

I claim:

The ornamental design for an index card holder, as shown and described.
